U.S. Cl. D47—6

The figure is a top plan view of a curtain fabric showing my new design, the leaf configuration on the right of the drawing figure is identical to that shown on the left but in a reversed position as to top and bottom as well as front to back, the diamond configuration shown in the center of the figure repeats on either side, the above design as shown and described repeats to the left and to the right to an indeterminate length, the width of the design is approximately three times that shown, both selvedge sides being as shown on the drawing and the center being plain and unornamented.

I claim.

The ornamental design for a curtain fabric, substantially as shown and described.
